UNITED STATES PATENT OFFICE.

ROBERT MOTT DE VIGNIER, OF HOLLIS TERRACE, NEW YORK, ASSIGNOR TO WESTERN ELECTRIC COMPANY, OF NEW YORK, N. Y., A CORPORATION OF ILLINOIS.

SWITCHBOARD-PLUG.

1,101,731.

Specification of Letters Patent. Patented June 30, 1914.

Application filed March 1, 1912. Serial No. 680,838.

To all whom it may concern:

Be it known that I, ROBERT MOTT DE VIGNIER, citizen of the United States, residing at Hollis Terrace, in the county of 5 Queens and State of New York, have invented a certain new and useful Improvement in Switchboard-Plugs, of which the following is a full, clear, concise, and exact description.

10 This invention relates to switchboard plugs, and more particularly to multiple conductor twin plugs, and has for its object to provide an improved plug of this general type which will be of few and simple parts, rigid in its construction, with all of the parts readily accessible and easily assembled.

According to the invention there is provided a body consisting of plate and stem 20 portions and a plurality of contact members or plugs secured to said plate and extending through the same so that the rear portions lie along side of the stem. Preferably a handle or shell is provided which is secured to the body and embraces the stem and rear portions of the plugs. The stem serves as a support for cord conductors which connect with the plugs. The rear portion of the stem may be cylindrical in 30 shape and extends entirely through the handle or shell.

Other features of the invention relate to the construction of the plug body for facilitating terminal connections, the means for attaching the plug to a cord and the arrangement and method of securing a handle or protecting shell over the parts.

In the drawings Figure 1 is a detail perspective view of a plug embodying this invention; Fig. 2 is longitudinal sectional view showing details of construction of the plug.

As shown in the drawings, there are provided two plugs or contact members, each 45 comprising a sleeve member 5 and a tip member 6 located in said sleeve member and insulated therefrom by means of a collar 7 and sleeve 8 of suitable insulating material. Each of the sleeve members 5 is 50 provided on one end with a screw-threaded portion 9 adapted to engage screw-threaded openings in a supporting plate 10 constituting part of the body of the plug. A shoulder 11 on each of said contact members bears against the outer face of the

plate 10. The inner end of each of the tip contact members 6 is provided with a screw-threaded portion 14 adapted to receive a clamping nut 12 by means of which the contact members 6 and insulating sleeve 8 are 60 secured to the sleeve contact member 5. A washer of insulating material 13 is inserted between the nut 12 and the inner end of the sleeve contact member 5.

Formed integrally with the plate 10 and 65 located between the screw-threaded openings therein is a stem 15, the outer end of which is in the form of a screw-threaded sleeve 16 through which a conductor cord 17 may be inserted. The sleeve opening 70 is made of a size such that the cord 17 can only be inserted therein by a turning motion which will cause the serving thereon to take into the threads of the sleeve. Provided on the stem 15 adjacent the inner end 75 of the sleeve 16 is a cut-away portion 18, which exposes the inner end of the said sleeve and provides a space for drawing conductors 19 and 20 of the cord into place. This cut-away portion 18 extends for a 80 short distance along the stem 15 and terminates in grooves 21, 21 upon opposite sides of said stem. In the assembling of the plug the conductors 19 and 20 are brought in through the sleeve 16, are crossed over each 85 other in the cut-away portion 18 and led through the grooves 21, 21, the inner ends of said conductors being adapted to be clamped between the clamping nuts 12, 12 and slotted clamping members 25, 25 secured to the inner ends of the tip contact members 6, 6. The plate 10 and stem 15 are preferably made of a casting thus avoiding the machining operation which would otherwise be necessary to provide the cut-away portion 90 and grooves in the stem 15.

The body portion of the plug is adapted 100 to be inclosed in a hard rubber or fiber casting 30, which is bored or hollowed out to the same general contour as the said body portion and clamping members 25, 25. Screws 31, 31 which are inserted through openings in the end of the shell engage the threads in the clamping members 25, 25 to clamp the shell 30 against the plate 10. The cord 105 shown is a three-conductor cord, and a third conductor 35 thereof is stripped of insulation and turned back onto the body of the cord so that when the cord is inserted into the sleeve 18 the conductor 35 is firmly se- 110

cured in contact with the stem 15 and thus in electrical connection with the sleeve contact members 5, 5. The conductors 19 and 20 will be electrically connected with the 5 tip contact members 6, 6. The openings in the shell 30, which receive the screws 31, 31, are counterbored to conceal the heads of said screws. In attaching the cord to the plug, the shell 30 is first slipped over the 10 cord, the conductors 19 and 20 passed through the sleeve 16 of the stem 15, and then the butt of the cord is forced into the sleeve with the conductor 35 turned back into position to be clamped between the cord 15 and the sleeve. After the cord has been inserted in the sleeve a sufficient distance, the conductors 19 and 20 are crossed over in the cut-away portion 18 of the stem 15 and laid into the grooves 21, 21 with their inner ends 20 which are stripped of insulation turned around the screw-threaded portion of the tip contact members 6, 6. The clamping members 25, 25 are then screwed into place and the shell 30 slipped over the body portion 25 of the plug and clamped by means of the screws 31, 31.

I claim:

1. In a switchboard plug in combination, a T shaped body comprising a plate and a stem formed integrally therewith said stem having grooves therein, a set of contact members electrically and mechanically secured to said plate, a second set of contact members insulated from said first mentioned 35 set of contact members and means on said second set of contact members adjacent said grooves for attaching cord conductors to said second set of contact members.
2. In a switchboard plug in combination, 40 a T shaped body comprising a plate and a stem formed integrally therewith said stem being provided with grooves and cord attaching means, sleeve contacts electrically and mechanically connected with said body, 45 tip contacts insulated from said sleeve contact members and having their inner ends located adjacent the grooves in said stem and clamping means for attaching cord conductors to the inner ends of said tip contact 50 members.
3. In a switchboard plug in combination, a T shaped body comprising a plate and a stem formed integrally therewith, said stem having a cut-away portion and grooves 55 formed in its body and being provided on one end with a screw threaded sleeve opening through said stem body adjacent to said cut-away portion to receive a conductor cord,

sleeve contacts attached to said plate, tip contacts insulated from said sleeve contacts 60 and having their inner ends located adjacent to said grooves and conductor attaching means on the inner ends of said tip contacts.

4. In a switchboard plug in combination, 65 a body comprising a plate and a stem formed integrally therewith, a pair of sleeve contacts secured to said plate, tip contacts passing through said sleeve contacts and said plate, conductor clamping members upon the 70 inner ends of said tip contacts, a shell inclosing said stem and clamping members and securing means for said shell co-operating with said clamping members.

5. In a switchboard plug in combination, 75 a body comprising a plate and a centrally located stem formed integrally therewith, a pair of sleeve contacts secured to said plate one upon either side of said stem, tip contacts passing through said sleeve contacts 80 and having their inner ends screw-threaded, screw-threaded clamping members upon the inner ends of said tip contacts, a shell for inclosing said stem and clamping members, and screws passing through said shell and 85 engaging with said clamping members.

6. The combination of a T-shaped body comprising plate and stem portions, a plurality of plugs secured to said plate, the rear ends thereof lying along the stem portion of the body, and cord conductors extending through and supported by said stem and connected to said plugs.

7. The combination of a T-shaped body comprising plate and stem portions, a plurality of plugs secured to said plate, the rear ends thereof lying along the stem portion of the body, cord conductors extending through and supported by said stem and connected to said plugs, and a shell embracing 95 said stem and the rear portions of 100 said plugs.

8. The combination with a T-shaped body consisting of plate and stem portions, of a plurality of plugs secured to said plate and 105 extending through the same, the rear portions of said plugs lying along the stem portion, and a shell secured to said body and embracing said stem and rear portions of the plugs.

In witness whereof, I hereunto subscribe my name this 28th day of Feb. A. D. 1912.

ROBERT MOTT DE VIGNIER.
